UNITED STATES PATENT OFFICE.

DAVID MYERS, OF JEFFRIS, WISCONSIN.

SAW GAUGE.

Application filed August 31, 1920. Serial No. 407,100.

To all whom it may concern:

Be it known that I, DAVID MYERS, a citizen of the United States, residing at Jeffris, in the county of Lincoln and State of Wisconsin, have invented certain new and useful Improvements in Saw Gauges, and I do hereby declare the following to be a full, clear, and exact description of the invention, such as will enable others skilled in the art to which it appertains to make and use the same.

This invention has relation to certain new and useful improvements in a saw swage and has for its primary object the provision of a tool of the character stated which will be of simple and compact form and which may be readily employed for setting and gaging the teeth of a saw.

The invention has for another object the provision of a saw swage of the character stated which will be constructed in such a manner as to include a raker swage, a lever set, a block set, bench set and a tooth gauge, the tool being constructed in such a manner that it may be readily positioned for use of any one of the several parts thereof.

With the foregoing and other objects in view, the invention consists in the novel construction and arrangement of cooperating elements as hereinafter more specifically set forth, claimed and shown in the accompanying drawings forming a part of the present application and in which:

Figure 1 is an elevation of the device, showing the same as being employed as a saw tooth gauge.

Figure 2 is a view similar to Figure 1 and taken at right angles thereto.

Figure 3 is an elevation of the tool employed as a block set.

Figure 4 is an elevation of the tool employed as a raker swage.

Figure 5 is a detail transverse section on the plane of line 5-5 of Figure 1.

Referring more in detail to the drawings in which similar reference characters designate corresponding parts throughout the several views, 1 indicates the body member or handle which is of rectangular form in cross section and also in longitudinal section, one end being cut away on one face, as shown at 2 and thereby reduced in thickness to provide a V-shaped raker swage 3 at the inner portion of the reduced or cutaway end 2 and extending in parallel relation therewith, said raker swage being formed on the

main portion of the handle 1, as will be readily understood by referring to the drawings. This end 2 is also provided with a slot opening on one side face so as to form a lever set 4. This is the same as the construction in my co-pending application Serial No. 175,861. The opposite end of the handle 1 is beveled upon one side face to form the block set 6, the head block 6 being formed on the same side of the handle 1 as the raker swage 3.

Projecting from the opposite side face of the handle 1 is an end peg 7 which is adapted to cooperate with a pair of side pegs 8 projecting from a similar face of a cross bar 9, which is mounted in a transverse recess 10 in the first mentioned side of the handle 1, adjacent the block 6, a corresponding socket 12 being formed in the center of the cross arm 9 so as to bring the corresponding side faces of the handle 1 and cross arm 9 into the same planes. A suitable securing member 13 is extended centrally through the cross arm 9 and through the handle 1 to assist in holding the cross arm 9 in proper position. This member may also be fastened in place by suitable binding mediums designated by the numeral 14 and consisting of glue, mucilage or the like, when the device is formed of a material such as wood. A tooth engaging screw 15 is threaded through the handle 1 adjacent the longitudinal center thereof and having its free or pointed end projecting from the second mentioned side face of the handle 1. The head 16 of the screw 15 may be countersunk in the first mentioned side of the handle 1, as shown in the drawings, if desired. This screw 15 may be readily adjusted and secured in adjusted position by a side locking screw 17 having threaded engagement in one of the edges of the handle 1 and adapted to contact with the thread of the screw 15 to prevent rotation thereof.

When the screw 15 has been properly adjusted, the tool may be readily employed as a saw tooth gauge by holding the handle in inverted position with the lugs 7 and 8 contacting with the side face of the saw while the end of the screw 15 engages the side of the tooth to be gauged. If the tooth has been properly set, all of the lugs 7 and 8 will contact with the side of saw body. If the tooth has not been set or bent sufficiently, however, the lug 7 will be spaced from the saw body. If the tooth has been

bent too far the lugs 8 will be spaced from the side of the saw body, thereby permitting the device to rock from side to side. After the tooth has been gaged, the lever set 4 5 may be employed to properly adjust the tooth, or if desired bend the tooth over still further, the block set 6 may be employed and the cross arm 9 will assist in holding the handle in proper position and 10 preventing the tooth from sinking into the wood too far.

When the raker swage 3 is employed, as shown in the drawings, the reduced end or cut away end portion 2 will contact with 15 one side of the saw body and the walls of the raker swage engage the raker tooth to cause proper spreading thereof as a blow is delivered to the upper end 5 of the handle 1. The cross arm 9 will also serve as a 20 means whereby the handle may be readily and properly held in proper position during use of the raker swage and the hand employed for holding the tool protected from the instrument employed to deliver the 25 blows to the upper end 5 of the handle 1.

It will be understood, by referring to Figure 2 of the drawings that when it is desired, this tool may be employed as a bench set, the saw being secured upon the bench and 30 the tool held in such a manner that one of the beveled corners 18 of the slotted ends is engaged against one side of the tooth of the set and blows delivered to the opposite side of the tooth by means of a hammer 35 or the like. This may be the preferred way of employing the tool for setting the saw

teeth when only a few of the teeth are to be set.

It is believed that the complete construction and operation of this improved tool 40 will be readily apparent from the foregoing paragraphs taken in connection with the accompanying drawings without further detail description.

While the preferred embodiment of this 45 invention has been shown and described, it will be understood that minor changes in the details of construction and arrangement of parts may be resorted to within the scope 50 of what is claimed without departing from the spirit of the invention.

What is claimed is:—

A gauge of the class described consisting of an elongated handle, said handle being a bar having one end constituting a saw tool, an arm disposed in cross relation to and in substantially the same plane as the handle, said arm projecting on opposite sides of and beyond the handle, said arm being located adjacent the end of said bar remote to the saw tool whereby a cruciform configuration is provided to constitute a hand grip when using the tool, and saw teeth-engaging lugs extending from the said 60 remote end and cross arm.

In testimony whereof I affix my signature in presence of two witnesses.

DAVID MYERS.

Witnesses:

ARTHUR ANDERSON,
A. J. O'MELIA.
